DESIGN FOR A CIGAR BOX CASE

Eugene W. Lilienfield, Chicago, Ill., assignor to Lilienfield Bros. & Co., Chicago, Ill.

Application November 4, 1940, Serial No. 96,291

Term of patent 3½ years

To all whom it may concern:

Be it known that I, Eugene W. Lilienfield, a citizen of the United States, residing at Chicago, in the county of Cook and State of Illinois, have invented a new, original, and ornamental Design for a Cigar Box Case, of which the following is a specification, reference being had to the accompanying drawing, forming a part thereof.

I claim:

The ornamental design for a cigar box case, substantially as shown.

EUGENE W. LILIENFIELD.
